UNITED STATES PATENT OFFICE.

HARRY H. SUTTON, OF LUCAS, SOUTH DAKOTA.

WIRE-GATE LATCH.

Application filed January 18, 1923. Serial No. 613,349.

To all whom it may concern:

Be it known that I, HARRY H. SUTTON, a citizen of the United States, residing at Lucas, in the county of Gregory and State 5 of South Dakota, have invented certain new and useful Improvements in Wire-Gate Latches, of which the following is a specification.

The present invention relates to improvements in wire gate latches and has for an 10 object the provision of an improved latch by the use of which the woven wire or other gate of flexible character may be maintained in a taut condition when closed.

15 The idea underlying the invention is to stretch the flexible or wire gate across the gate opening in such wise that the gate presents the same effective barrier as the remainder of the wire fence and affords no 20 loop holes for the escape of small animals as occurs frequently when gates of this character sag.

Another object of the invention is to accomplish these results simply and inexpensively and by a latch mechanism that is comparatively easy to operate.

A further object of the invention is to provide a latch mechanism in which the closing movement will be effective to apply 30 great force to the stretching of the wires without, however, imposing a too great burden upon the operator.

A still further object of the invention is to provide a mechanism of this character 35 which will be compact in its arrangement and assembly and attachable to the fence post and the gate without entailing any alterations of the standard constructions.

With the foregoing and other objects in 40 view, the invention will be more fully described hereinafter, and will be more particularly pointed out in the claims appended hereto.

In the drawings, wherein like symbols 45 refer to like or corresponding parts throughout the several views,

Figure 1 is a fragmentary view, with parts broken away showing the gate and the improved latch mechanism in front elevation.

50 Figure 2 is a plan view of the same parts.

Figure 3 is a vertical section, with parts broken away through the fence at one of the gate posts.

55 Figure 4 is a view similar to Figure 1,

except that the mechanism is shown as unlatched and the gate partially collapsed.

Figure 5 is a plan view of the latch mechanism in the open position.

Figure 6 is a fragmentary view, with parts 60 broken away, of one of the gate bars with the keeper thereon.

Figure 7 is a view in elevation of the modified form of gate construction with the latching mechanism shown unlatched. 65

Figure 8 is a similar view with the parts latched, and

Figure 9 is a plan view of the device shown in Figure 8.

Referring more particularly to Figures 1 70 to 6 inclusive, 10 designates wire fence of any known character and 11 a fence post erected at one side of the gate opening and having eye bolts 12 therein for coupling swingingly to complementary fastenings 13 75 upon the gate bar 14.

The gate member is also provided with an opposite end vertical bar 15 and with an intermediate bar or rail 16, wire mesh or fabric 17 being stretched between the end 80 bars and attached to the intermediate bar or rail 16 so that the mesh of the gate is similar to the mesh 10 of the general fence structure and extends down as close to the ground and close to the gate posts 11 and 18 for the purpose of barring the passage of pigs or other small animals. The fence may comprise a greater number of bars or rails but three are sufficient for cooperating with the improved latch mechanism and to this end the 85 bar 15 is provided near its top portion with an eye bolt 19, to which is connected a chain 20 having a suitable number of links adapted to be selectively fitted within the volute end 21 of a latch bar 24 which is pivotally 90 carried upon the post 18 as best seen in Figure 3.

In this Figure 3 a bolt 25 is shown as passing horizontally through the post and at right angles to the plane of the fence fabric. 100 This bolt is secured as by a nut 26 at one end bearing against a washer 27 fitted against the wood of the post. The head 28 of the bolt extends a considerable distance beyond the opposite face of the post and is beveled or countersunk into a washer 29 which extends about the outer face of the latch bar 24. The latch bar is perforated 105 at this point in order to extend about the shank of the bolt and about the cylindrical 110

portion 22 of a washer having a flange 23 engaging against the opposite side face of the latch bar 24. The washer extends about the shank of the bolt 25 and engages at its flanged end against a diagonal brace 30 which is connected also by means of the bolt 25 to the upper end of the gate post 18. The brace extends down and is connected to an adjacent post or into the ground, in accordance with a well known manner in fence construction.

The gate rail 15 is provided near its lower end with an eye bolt 31 having a relatively large eye 32 for cooperating with a hook 33 upon a lower latch bar 34 secured as by a bolt 35 pivotally to the post 18 directly beneath the bolt 25. A nut 36 and washer 37 are employed to hold the pivot bolt 35 upon the post 18 as shown in Figure 3; and a washer 38 surrounds the opposite projecting head end of the bolt 35 to space the bar 34 away from the post to give said bar free movement. The head of the bolt 35 is countersunk in the engaged portion of the latch bar 34.

As seen probably to best advantage in Figure 4 the latch bars 24 and 34 are connected by a reach bar 39 pivoted to the bar 34 as indicated at 40 and to the upper bar 24 as indicated at 41. These pivot bolts are preferably countersunk in both of the bars as indicated at 41 in Figure 3. The upper latch bar 24 is provided with a handle extension 32 lying beyond the pivot point 41 and the reach bar 39 is off set as indicated at 43 and the lower latch bar 34 is similarly off set as at 44 in order to permit movement of the bars passed one another in moving from the position shown in Figure 1, in which the gate is latched, to the position shown in Figure 4, where the latching mechanism is moved to open position. In Figure 1 it is clear that the lower bar 34 is pivoted in the same plane with the upper latch bar 24 and the off set portion 44 therefore becomes necessary as the volute hook end 21 of the upper latch bar 24 swings past the offset portion of the lower latch bar 34. This will be clear from Figure 1.

Now the handle portion 42 of the upper bar 24 is adapted to engage in the keeper carried upon the intermediate gate rail 16 when the parts are in the position shown in Figure 1. This keeper is shown more particularly in Figure 6 wherein a base strip 45 is shown to be secured as by the bolts 46 to the rail 16, the base strip being composed of strap metal and being returned upon itself at its upper end and directed downwardly to form the substantially inverted U-shaped keeper open at its base to receive the extension part 42 and being rolled over at its lower free edge as indicated at 47 to extend about one member of the link 48. This link 48 forms a pivotal latch for holding the exten-

sion 42 against escape downward, and from being pushed downward by the animals or by children or avoiding any accidental or casual opening of the gate.

Now in operation, the parts initially assume the position shown in Figure 4 and the eye 32 is engaged over a hook 33 of the lower latch bar, while the chain 20 is secured about the volute end 21 of the upper latch bar 24. Under these circumstances the gate is substantially in the condition illustrated in which the rails are drawn together by the sagging of the wire and the fabric is raised above the ground. After making a proper engagement of the parts with the latch bars, such latch bars are then swung upwardly by grasping the handle or extension part 42. The upper bar 24 is swung through a complete semi-circle or through 180 degrees, thus causing a direct pull upon the chain 20, the engaged link sliding about in the volute end 21, and the volute character of this end will present a sufficient obstruction to the accidental disengagement of the chain even when the parts are in the inverted position shown in Figure 1. The reach bar 39 will of course be drawn upon during this movement and it will serve to rotate the lower latch bar 34 through approximately 90 degrees until said latch bar finally brings up with its length extending vertically along the post 18. The hook 33 will have pulled upon the lower portion of the gate structure and it will be found that the gate is stretched entirely across the gate opening with the gate bars lying vertically and no means of escape being provided with the gate any more than at other portions of the fence. The arrangement of the four pivots for the latch bars provide for this movement and for the parallelism of the reach bar 39 with the upper latch bar 24 when the parts are in the latched position shown in Figure 1. The extension 42 is slipped beneath the link 48 which is automatically swung back but moves again across the opening due to the force of gravity. In this condition the extension 42 cannot escape except by the positive opening of the link 48 during the movement of the part 42 downwardly.

Now the mechanism already described is suitable for small animals but where cattle are to be confined a somewhat cheaper construction may be employed with equally good results.

Referring to Figures 7, 8 and 9 for this structure we have the horizontal fence wire 50 wound about the gate post 51 and secured thereto as by staples 52, the wire being continued as indicated at 53 to form the fabric for the gate. By reason of this construction the end bar for the gate adjacent the post 51 is no longer required. The intermediate gate bar is indicated at 54 and the end rail by 55, these parts being

composed of rough lumber or other suitable material and being affixed to the gate wire. The gate rail 55 is extended downwardly and engaged in a staple or loop 56 at the 5 base of the other gate post 57 which carries the latch bar 58 having the volute end or hook 59 engaged with the chain 60 secured to the gate rail 55. The latch bar 58 is pivotally secured to the post 57 as by the 10 bolt or pin 61 and is enabled to swing through a semicircle to bring its handle portion into engagement with the keeper 62. The keeper and its link 63 are as heretofore described and the engagement of the chain 15 60 with the latch bar will now be understood, the open position of the parts being shown in Figure 7 and the closed position in Figure 8 accomplished by swinging the latch bar 58 through 180 degrees and 20 gaging its end in the keeper 62 which is upon the gate rail 54.

When the latch bar is swung over the gate rail 55 it is moving toward the post 57, pivoting about the staple or loop 56 and 25 stretching the gate wires taut. When the latch device is released the gate wires will sag and the lower projecting end of the gate rail 55 may be lifted out of the wire 56 so as to permit the gate to be swung 30 about.

It will be appreciated from the foregoing that both forms of the device are simple, inexpensive yet effective in action and permit of the ready opening and closing of the 35 gate. The latch device forms an effective closure not apt to be loosened unintentionally. The device will always maintain the gate wires in good condition through holding them taut.

I do not wish to be restricted to the size, 40 form and proportions of the various parts, and obviously changes could be made in the construction herein described without departing from the spirit of the invention, it being only necessary that such changes 45 fall within the scope of the appended claims:

I claim:—

1. In combination with a flexible gate, a gate post, a pivoted latch bar on said post and having a hook, means carried by the gate 50 to engage said hook, and a keeper on the gate for receiving a part of the latch.

2. In combination with a flexible gate, a gate post, a pivoted latch bar on the post having a hook, a chain carried by the gate 55 for selective engagement with the hook, and a keeper on the gate for receiving a portion of the latch bar.

3. In combination with a gate, a gate post, a pair of latch bars pivoted to the post, a 60 reach bar connecting said latch bars, means on the gate to detachably connect with said latch bars, and a keeper on the gate to receive one of the bars.

4. In combination with a wire gate having end bars and an intermediate bar, a keeper upon the intermediate bar, an eye upon one end bar, a chain upon the same end bar, latch bars having hooks pivoted to the post, a reach bar connecting said bars, said 70 bars having offset portions, one of said bars having an extension to engage said keeper.

In testimony whereof, I have affixed my signature in presence of two witnesses.

HARRY H. SUTTON.
